(57) **CLAIM**

The ornamental design for a long stem, electric socket tea light candle adapter, as shown and described.

DESCRIPTION

FIG. 1 is a perspective front and top view of a long stem, electric socket tea light candle adapter in a first configuration, showing the first variant of my design;

FIG. 2 is a front view thereof, the rear view being a mirror image;

FIG. 3 is a right side view thereof, the left side view being a mirror image;

FIG. 4 is a top view thereof;

FIG. 5 is a bottom view thereof;

FIG. 6 is a right side view thereof in a second configuration;

FIG. 7 is a right side view thereof in a third configuration;

FIG. 8 is a perspective front and top view of a long stem, electric socket tea light candle adapter, showing the second variant of my design;

FIG. 9 is a front view of the second variant, the rear view being a mirror image; and,

FIG. 10 is a right side view of the second variant, the left side view being a mirror image, and the top and bottom views being the same as FIG. 4 and FIG. 5 respectively.

The drawings show two variants of my design. The two variants do not differ substantially from each other. FIGS. 1 to 7 show the first variant and FIGS. 8 to 10 show the second variant. The difference between the two variants is in the shape of the bead-like members along the stems thereof. The first variant has cone-shaped bead-like members and the second variant has spherical bead-like members.
